UNITED STATES PATENT OFFICE.

WILLIAM H. MINER, OF CHICAGO, ILLINOIS.

DRAFT-ARM.

1,128,346.

Specification of Letters Patent. Patented Feb. 16, 1915.

Application filed February 28, 1914. Serial No. 821,871.

To all whom it may concern:

Be it known that I, WILLIAM H. MINER, a citizen of the United States, residing in Chicago, in the county of Cook and State 5 of Illinois, have invented a new and useful Improvement in Draft-Arms, of which the following is a specification.

This invention relates to improvements in draft arms for railway car underframes. 10 One object of the invention is to provide a two-piece draft arm which may be attached to the wooden sills of a car underframe to brace the sills and so arranged that the buffing and pulling shocks are 15 transmitted in an efficient manner to the sills.

Another object of the invention is to provide a draft arm of the character above indicated which may be made in the form of 20 a malleable casting and which is cheaper and lighter than structures hitherto used.

The invention furthermore consists in the improvements in the parts and devices and in the novel combinations of the parts and 25 devices herein shown, described or claimed.

In the drawing forming a part of this specification, Figure 1 is a part vertical section, part side elevation of the end portion of a car underframe and showing my 30 improvements in connection therewith. Fig. 2 is a part top plan view and part horizontal section of the structure shown in Fig. 1. Fig. 3 is a transverse vertical section taken on the line 3—3 of Fig. 2, and 35 Figs. 4 and 5 are similar sectional views taken on the lines 4—4 and 5—5, respectively, of Fig. 1.

In said drawing 10, 10 denote the wooden center sills, 11 the end sill and 12 the dead 40 block or buffer beam; said parts being arranged in the usual manner, and 13 denotes the body bolster casting which, as shown, is provided with recesses 14, one on each side of the king pin, through which extend 45 the ends of sub-sills 15. Each draft arm is shown as comprising a front member A and a rear member B, said members having overlapping portions 150 and 160, respectively, riveted together as shown in 50 Figs. 1 and 2. The member A, at its forward end, extends beneath the end sill and buffer beam as shown at 16 and is provided with a shoulder 117 to abut the inner side of the end sill. The member A is also provided 55 with a plurality of integral front and rear stops 17, 17, intermediate stops 18, 18

and limiting stops 19, 19. The member A has a lower flange 20, upper flange 21 which extends beneath the center sill 10 and by which the draft arm is secured thereto by 60 bolts and nuts 22, 23. At its inner end the member A is provided with a transversely extended flange 24 against which the outer end of the sub-sill 15 abuts whereby the buffing shocks are transmitted from the 65 member A directly in line with the sub-sill 15. The member B is substantially of an angular cross section throughout its length and has a vertical web 25 and horizontal web 26, the latter being placed between the 70 center sill 10 and the sub-sill 15 as shown most clearly in Fig. 5. The member B is secured to the sills by vertically extending bolts 27 and by transversely extending bolts 28, the latter, on the outer sides of the center sills, passing through plates 128 to prevent the bolts from pulling through the 75 wooden sills. Over the bolster 13 the member B is recessed as shown at 29 to fit the top plate of the bolster and the vertical web 80 25 is upwardly extended as indicated at 30. Each member B is also provided with a shoulder 31 to support truss rod saddles 32, see Figs. 1 and 2. The overlapping end 160 of each member B is extended down to a 85 point below the lower plate of the body bolster and such extension is formed with a shoulder 33 which abuts against the body bolster. Each of said overlapping extensions is also provided at its forward end 90 with another shoulder 34 which co-operates with a correspondingly located shoulder 35 in each member A, the structure just described providing an exceedingly rigid and 95 solid connection between the members A and B of each draft arm.

From the preceding description it will be seen that the draft arm which I have provided extends from the end sill over the bolster and to the rear of the latter 100 and because of the fact that it is made in two parts, the same may be made in the form of malleable castings. Each member A performs not only the function of a stop casting but in combination with the 105 member B also braces and reinforces the center sill. The draft arm provided is also of rigid and substantial construction although the same is relatively light.

Although I have herein shown and described what I now consider the preferred embodiment of my improvements, yet it 110

will be understood that various changes and modifications may be made without departing from the spirit of the invention and all such changes and modifications are contemplated as come within the scope of the claims appended hereto.

I claim:

1. In a car underframe, the combination with wooden sills, of a draft arm secured thereto, said draft arm comprising two members overlapped and secured together between the bolster and the end sill of the car, the inner member of the draft arm extending over and to the rear of the body-bolster and secured to the wooden sill and adapted to brace the latter, the front member being also secured to the sill and bracing the latter.
2. In an underframing for railway cars, the combination with a wooden sill extending to the end sill of the car, of a draft arm secured to said sill, said draft arm comprising two malleable castings having overlapped ends secured together, the said draft arm extending over the body-bolster of the car and to the rear thereof and secured to and bracing the wooden sill from the end thereof to a point at the rear of the bolster.
3. In underframing for railway cars, a draft arm comprising two malleable castings

having overlapped ends secured together, one of said castings serving as a stop member and having a shoulder at its inner end adapted to abut the end of a longitudinal sill, the other of said castings extending over the body bolster and to the rear thereof and having a shoulder engaging one side of the body bolster, substantially as specified.

4. In underframing for railway cars the combination with center sills, bolsters and draft arms passing over the bolsters of saddles for truss rods, said saddles being mounted upon the draft arms and located on the inner sides thereof, substantially as specified.

5. In an underframe for railway cars, the combination with wooden center sills having wooden sub-sills secured thereto, said sub-sills terminating adjacent the body-bolsters, of a body-bolster, and draft arms, said draft arms each comprising a member secured to the center sill and arranged to brace the same and having also flanges abutting the body-bolsters and a sub-sill end.

Signed this 26 day of February, 1914, in the presence of two witnesses.

WILLIAM H. MINER.
